MATERIAL HANDLING APPARATUS

Ray C. Kivley, Oak Park, Ill., assignor to Western Electric Company, Incorporated, New York, N. Y., a corporation of New York

Application September 19, 1936, Serial No. 101,587

9 Claims. (Cl. 266--7)

This invention relates to material handling apparatus, and more particularly to portable pickling barrels.

One object of the present invention is the provision of a simple and efficient material handling apparatus.

In the preferred embodiment of the invention, a supporting framework adapted to be transported by crane between various pickling and rinsing vats, is provided with a barrel journaled in the end portions of the framework and adapted to be rotated by a self-contained motor mounted upon one of the ends of the framework, whereby a unitary structure is provided which may be shifted at will from one pickling vat to another, one end of the framework being provided with a pair of fixed brackets for engaging the end of a pickling vat, and the other end of the framework having pivoted thereon a cross arm for engaging the sides of pickling vats.

A better understanding of the invention may be had by reference to the following description when considered in conjunction with the accompanying drawing, wherein

Fig. 1 is a side elevational view of a portable pickling barrel and its supporting and driving mechanisms formed in accordance with one embodiment of the invention;

Fig. 2 is a plan view of the apparatus shown in Fig. 1, parts being broken away to conserve space and to more clearly illustrate certain features of the apparatus, and

Fig. 3 is a fragmentary end elevational view of the structure shown in Fig. 1.

Referring now to the drawing wherein like reference numerals indicate the same parts throughout the several views, the numeral 5 indicates generally a supporting framework for rotatably supporting a pickling barrel 6. The framework 5 is comprised of a horizontally disposed I beam 7 having an eye 8 secured thereto by being clamped over the upper flanges of the I beam for receiving a crane hook (not shown). At the left end (Fig. 1) of the I beam 7, the lower flanges thereof are cut away as shown at 9, and a pair of vertically disposed members 10 and 11 are secured to opposite surfaces of the web portion of the I beam.

A brace 12 is secured to the I beam and twisted for insertion between the members 10 and 11 to which it is also secured, and the lower portion of the members 10 and 11 are bent apart as shown at 13 and 14 to form an inverted V. Secured to the members 10 and 11 adjacent their lower end are a pair of plates 15 and 16. An aperture is

formed in each of the plates 15 and 16 to receive a pivot pin 17, for pivotally supporting a bar 18. The amount of movement of the bar 18 about the pivot pin 17 may be limited by set screws 19 and 20 threaded in the ends of a plate 21 secured to the lower ends of the members 10 and 11, and to the plates 15 and 16. A journal block 25 is secured to the plate 18 by means of bolts 26-26 and a channel supporting member 27 having cross pieces 28 welded thereto is also secured to the plate 18 by means of bolts 29. Each of the flanges of the channel-shaped supporting member 27 is cut away as shown at 30, so that a shaft 31 journaled in the journal block 25 may extend freely through the flanges of the channel-shaped member. The pickling barrel 6 is mounted upon the shaft 31 between the vertically disposed members 10 and 11, and a pair of vertically disposed angle members 41 and 42. The angle members 41 and 42 are secured to the ends of a horizontally disposed angle member 43 adjacent its ends. The horizontally disposed angle member 43 is secured in any conventional manner at its middle portion to the I beam 7 and corner braces 44 and 45 are welded to the I beam and to the angle members 41 and 42 to form a rigid substantially rectangular framework at the right end (Figs. 1 and 2) of the supporting framework 5.

Adjacent the lower portion of the angle members 41 and 42 a plate 46 is secured thereto. This plate 46 forms a portion of the housing indicated generally by the numeral 47 to which supporting brackets 48 and 49 and a journal block 50 are fixed. The supporting brackets 48 and 49 are adapted to engage the end of a pickling vat shown in dot and dash lines at 51 when the barrel is in use and cooperate with the pivoted channel-shaped supporting member 27 to support the barrel 6 in the vat 51. The journal block 50 rotatably supports the right end (Figs. 1 and 2) of the shaft 31 to which there is affixed a driving gear 60 meshing with a spur gear 61 driven through a speed reducer 62 of conventional form by a motor 63. The motor 63, speed reducer 62, and gears 61 and 60 are enclosed in the housing 47 which has a base 64, a top 65, ends 67 and 68 and a hinged door 66, whereby access may be had to the motor and speed reducer.

The drum 6 is provided with a removable cover 10 which may be removed to place parts to be treated in the barrel and which is normally held in place on the barrel by a spring pressed latch member 71. After parts have been placed in the barrel 6 at any convenient location, the barrel and supporting framework 5 may be picked up by a

crane, the hook of which may be connected to the crane hook 8, and the barrel may be moved to a series of cleaning or pickling baths without removing the parts from the barrel, thereby 5 eliminating a great number of manual operations formerly required for transferring the articles to be treated from one barrel to another where a separate pickling barrel was provided for each pickling bath. When the barrel is placed in a 10 vat, the two supporting brackets 48 and 49 will engage the end of the vat and the channel-shaped supporting member 27 will engage the sides of the vat, this latter member being made long enough to extend over the sides of any of the 15 vats which are to be used and being pivotally connected to the framework to compensate for any irregularity in the height of the side walls of the various vats in which the barrel is to be placed during the desired sequence of operation. 20 Preferably power is supplied to the motor for rotating the barrel during treatment of the parts therein by a conductor cord which may be plugged into sockets located conveniently with respect to the vats. After the articles in the barrel have 25 been treated in any desired manner, the barrel may be removed from the pickling vat by means of the crane hook and carried to any desired location where, after the removal of the cover plate 10 the motor may be started to rotate the 30 barrel and drop the parts therefrom.

Although a specific embodiment of the invention has been described, it will be understood that the invention is subject to many modifications and is to be limited only by the scope of the 35 appended claims.

What is claimed is:

1. A material handling apparatus, comprising a framework provided with an eye adapted to receive a crane hook whereby it is transportable, 40 a barrel rotatable in said framework, and a driving mechanism mounted upon said framework, said framework having a pair of members fixed thereto and a member pivoted thereon to a limited extent for supporting the framework on the sides of vats to hold the barrel in 45 treating baths in the vats.

2. In a material handling apparatus, a portable framework, a driving motor supported at one end of said framework, a shaft journaled in said 50 framework to be driven by said motor, and supporting means attached to said framework for holding the framework in a predetermined position said supporting means including a pair of fixed support members and a pivoted support 55 member.

3. A self-contained portable pickling barrel unit, comprising a frame, a motor mounted on one end of said frame, a barrel rotatably supported between the ends of the frame and connected to the motor to be driven thereby, and a support for said barrel and frame between the barrel and the motor slightly below the connection therebetween and adapted to rest on the 60 wall of a vat or the like.

4. In a material handling apparatus, a portable framework, a driving motor supported at one end of said framework, a shaft journaled in said framework to be driven by said motor, a barrel rotatable with said shaft, and supporting means 65 for holding the framework in a predetermined position in a treating vat, said supporting means including a pair of fixed support members for engaging one side of a vat, and a pivoted support member for engaging opposite sides of a vat

to provide a four point support for the framework while holding the barrel in a treating vat.

5. In a material handling apparatus, a framework, a barrel rotatable in said framework, a driving mechanism for rotating said barrel, and a support for supporting said framework on a treating vat said support being attached to the framework and including a member pivoted to said framework for engaging spaced portions of a vat. 10

6. In a portable material handling apparatus, a framework provided with an eye adapted to receive a crane hook whereby the framework may be transported, a driving motor supported by said framework, a tumbling barrel driven by said motor and supported by said framework, spaced apart supports fixed to said framework for supporting the framework on the end of a vat, and an elongated member pivoted to said framework for supporting it on the sides of said vat. 15 20

7. In a material handling apparatus, a rotatable tumbling barrel, a motor for driving said barrel, and a framework for supporting the motor and barrel comprising a horizontal I beam, an eye fixed to said I beam to receive a crane hook for transporting the framework, a transversely disposed angle member secured to said I beam, a pair of substantially vertically disposed angle members fixed to said horizontally disposed angle member for supporting the motor at one end of said framework, a pair of support brackets connected to said vertically disposed angle members, a pair of flat members secured to the opposite end of said I beam, and a member of U-shaped cross section pivoted to said flat members at the 30 end thereof away from the I beam. 35

8. In a material handling apparatus, a rotatable tumbling barrel, a motor for driving said barrel, and a framework for supporting the motor and barrel comprising a horizontal I beam, an eye fixed to said I beam for transporting the framework, a transversely disposed angle member secured to said I beam, a pair of substantially vertically disposed angle members fixed to said horizontally disposed angle member for supporting the motor at one end of said framework, a pair of support brackets connected to said vertically disposed angle members, a pair of flat members secured to the opposite end of said I beam, a member of U-shaped cross section pivoted to said flat members at the end thereof away from the I beam, and means for limiting the amount of pivotal movement of said pivoted member. 45 50

9. In a material handling apparatus, a rotatable tumbling barrel, a motor for driving said barrel, and a framework for supporting the motor and barrel comprising a horizontal I beam, an eye fixed to said I beam for transporting the framework, a transversely disposed angle member secured to said I beam, a pair of substantially vertically disposed angle members fixed to said horizontally disposed angle member for supporting the motor at one end of said framework, a pair of support brackets connected to said vertically disposed angle members, a pair of flat members secured to the opposite end of said I beam, a supporting member pivoted to said flat members at the end thereof away from the I beam, and a pair of adjustable members for limiting the amount of pivotal movement of said pivoted member. 60 65 70
